UNITED STATES PATENT OFFICE.

VINCENT G. APPLE, OF DAYTON, OHIO, ASSIGNOR TO THE APPLE ELECTRIC COMPANY,
OF DAYTON, OHIO, A CORPORATION OF OHIO.

GEARING.

1,148,884.

Specification of Letters Patent.

Patented Aug. 3, 1915.

Application filed December 16, 1912. Serial No. 736,954.

To all whom it may concern:

Be it known that I, VINCENT G. APPLE, a citizen of the United States, residing at Dayton, in the county of Montgomery and 5 State of Ohio, have invented certain new and useful Improvements in Gearing, of which the following is a specification.

My invention relates to improvements in transmission gearing and has especial reference to means for starting the internal combustion engine that may be used to propel 10 a motor car, and the relation of said starting means to said engine.

One of the objects of my invention is to 15 provide a dynamo electric machine and speed reduction gearing which will have an axial over all dimension substantially that of the dynamo armature alone, thereby greatly compacting the device and making it particularly 20 adapted to mounting coaxially with the engine shaft either at the front or rear thereof.

Another object of my invention is to provide a self-starting motor of suitable construction and to mount it in front of the engine in coaxial relation therewith, with its main support resting in the crank lever bearing so that my improved motor may be quickly substituted for the usual manually-operable crank lever, for starting the engine.

Other and further objects of my invention such for example as the gearing itself will become readily apparent to persons skilled 35 in the art from a consideration of the following description when taken in conjunction with the drawings, wherein:—

Figure 1 is a front elevation of an automobile, showing my motor in place; Fig. 2 40 is a broken-away side elevation of the front end of the vehicle; Fig. 3 is an enlarged central horizontal section of the motor; and Fig. 4 is a similar transverse section taken on line 4—4 of Fig. 3.

45 In all the views the same reference characters indicate similar parts.

In the exemplification which I have chosen for the clear disclosure of my invention, 10 is the bonnet or hood of an automobile, 11 is the radiator arranged in the usual manner upon the chassis or frame 12, provided with semi-elliptical springs 13, and having traction wheels 14. The internal combustion engine 15 is mounted in the usual manner on 50 the chassis within the bonnet and the axle 55

16 is adapted to support the front end of the automobile upon the traction wheels. A cross sill 17 is secured to the respective bars or side frames 12, and provides a bearing 19 which is usually employed for supporting 60 and guiding the manually-operable crank lever.

20 is the frame forming a substantial part of the housing and also the magnetic path for the field magnets 21 of the dynamo. It 65 is provided with a perforated hub 22, which is adapted to fit neatly in the crank lever bearing 19. It is also provided with four rearwardly projecting arms 21, 22, 23, and 24, that are secured to the cross sill 17, as 70 by means of bolts 25 and 26. The hub 22 of the dynamo frame is perforated to provide rotary bearing for an elongated sleeve 27 which, in some conditions of operation, is adapted to turn in the said bearing. 75

28 is the engine coupling to which the motor shaft 29 is adapted to be removably connected by means of the pin 30. The shaft 29 is enlarged, as at 31, to form one member of the roller clutch and, as at 32, 80 it is provided with ball bearings 33. It is also screw threaded at its outer end, as at 34, to permit the mounting of the screw threaded nuts 35 thereon for holding a member of the roller bearing 33 in place. It is 85 also provided with a transversely positioned pin 36 as a means for turning the shaft 29, and through the connecting coupling 28, the engine shaft, by the manually-operable crank arm or lever in usual manner. A cap 90 37 is removable for insertion of said lever.

The field magnets consist of a series of magnetic rings having eight salient inwardly-projecting poles. The number of poles of the machine may be varied according to the ideas of the constructor, as my invention is not limited to the number of poles that it shall contain. 95

Bolts or studs 38 are adapted to take through the laminæ of the field magnet core 100 and enter the main frame 20 for the purpose of securing the magnetic field portion to the frame. The bolts 38 project outwardly beyond the field to provide a means for securing the removable jacket or cover 39 in 105 place. A rotatable armature 40 consists of a series of laminæ of rings held together by screws 41 which also secure them to the rotating shell 42. The shell 42, with a plate 43, forms a housing upon which the arms 110

ture core is mounted in a manner heretofore described. Within this housing is contained a pair of gear wheels 44 and 45 that are secured together on the shaft 46 so that they turn as one. There is a slight difference in diameter of these wheels, the wheel 44 having one or two more teeth in its circumference than the wheel 45. They are both mounted on a sleeve which has bearing 10 on the stud 46, the latter being secured in the shell 42 and the plate 43. In the drawings I have shown three pairs of such wheels, but it is, of course, obvious that one or any convenient number of pairs may be used.

15 Mounted on the shaft 29 is a gear wheel 47 which meshes constantly with the gear wheel 45 and is secured to the shaft 49 by means of keys 48. The sleeve 27 is radially enlarged, as at 49, to provide a gear 50 which is constantly in mesh with the gear wheel 44. Secured to the sleeve 27 is a brake wheel 51 rotatably attached thereto by means of the keys 52—52 and the screw 53. A brake band 54 passes over the brake wheel 51 and is adapted to be tightened thereon by means of lever 55 and cam members 56 and 57, operating on a rod 58, such parts serving to draw the two ends of the brake band together for the purpose of holding the brake wheel stationary at the time when the engine is to be started. This feature, and several others of my invention not herein claimed, are clearly disclosed and claimed in a co-pending application filed November 9, 1912, 30 and identified by Serial No. 730,377.

60 is a roller clutch interposed between the shaft 29 and the armature 40. A bearing ring 61 of the clutch is secured in the shell 42 of the armature. A ball bearing 63, 40 one member of which is supported on the sleeve 27 and the other member in the plate 43, serves as another bearing for the armature 40. Upon a flanged ring 64 the commutator 65 is mounted, the ring being secured to the shell 42 which carries the armature 40 and the commutator rotating therewith. A series of brushes 66 bear upon the commutator segment in the usual manner.

50 The operation of starting the motor is as follows:—The brake wheel 51 is held firmly in place by application of the brake band 54, through the operation of the rod 58 and the lever 55 in a manner clearly understood. When it is desired to rotate the engine shaft 55 until the engine becomes self propelling, the motor is energized by suitable electric current, (passing through electrical conductors which for sake of clearness are not shown in the drawings), when the armature will begin to rotate, in clock-wise direction looking toward the front of the automobile. The brake wheel 51 and the connecting sleeve 27 now being stationary, the rotation of the armature 40 and the differential gears 44 60 and 45 carried thereby move the shaft 29 at

a speed much less than that at which the armature is rotated, and thereby the engine shaft will be rotated at a relatively low speed. When the shell 42 of armature 40 is rotating at a higher speed than that of the shaft 29, the centrifugally acting clutch 60 will not engage these two parts and therefore the connection between the armature 40 and the shaft 29 is necessarily through the train of speed-changing gearing heretofore 70 described. When the engine becomes self propelling, the brake band 54 is released from the wheel 51 and the centrifugal effect of the rotating parts will cause the clutch 60 to engage the shaft 29 and the shell 42 of 75 armature 40, thereby connecting the armature directly with the engine shaft. At this time the sleeve 27 will be rotated with the shaft 29, the gear wheels 44 and 45, contained in the housing provided by the shell 80 upon which the armature is mounted, will not be rotated on their own axes, and the dynamo electric machine will be driven as a generator directly by the engine, without any intervening gearing.

90 Should the dynamo electric machine be out of order or for any reason should it be desirable to start the engine by the usual manually-operable crank lever, the cap 37 is removed and the crank lever is inserted on 95 the end 34 of the shaft 29 until it is in engagement with the pin 36, when the engine shaft may be directly rotated by means of the crank lever and without the necessity of rotating the armature, the sleeve 27 being 100 rotated by the instrumentality of the gearing connection. Should it be desirable at any time to resume operation of the manually-operable crank lever, the dynamo electric machine may be removed and the crank 105 lever restored to its original position in the bearing 19 without the necessity of changing the construction of the automobile.

110 While I have herein described a single embodiment of my invention, for the purpose of clear disclosure, it is evident that many changes may be made in the structure within the spirit and scope of the appended claims.

115 What I claim is:

1. The combination with a dynamo electric machine, of a shaft to be rotated; an armature support, rotatably mounted upon said shaft, said support provided with an opening and speed reducing gearing positioned within the said opening and connecting the armature with the said shaft.

120 2. The combination with a dynamo electric machine, of a shaft to be rotated; a cup shaped member rotatably mounted upon the said shaft and carrying at its periphery the armature windings; a disk rotatably mounted upon the said shaft and secured at its periphery to the open end of the cup shaped member forming a closure therefor; and 125 130

speed reducing gearing connecting the armature with the shaft and positioned within the cup shaped member.

3. The combination with a dynamo electric machine, of a shaft to be rotated; a hollow armature support rotatably mounted at each end about the said shaft, speed reducing gearing interposed between the armature support and the shaft; means for disconnecting said speed reducing mechanism to prevent transmission of power therethrough; and a clutch for positively connecting said armature support with the said shaft, said speed reducing gearing and said clutch being positioned within the confines of the said hollow armature support.

4. The combination with a dynamo electric machine, of a shaft to be rotated; a hollow armature support rotatably mounted upon the said shaft, the walls of the said support being substantially parallel; a spindle parallel to the said shaft and having its ends secured in the parallel walls of the armature support; a pair of connected pinions rotatably mounted upon the said spindle; a gear positioned within the hollow portion of the armature support engaging with one of the pinions and rigidly secured to the shaft; a second gear rotatably carried by the shaft and engaging with the other pinion and means for stopping the rotation of the last mentioned gear.

5. The combination with a dynamo electric machine, of a shaft to be rotated; a hollow armature support rotatably mounted upon the said shaft, the walls of the said support being substantially parallel; a spindle parallel to the said shaft and having its ends secured in the parallel walls of the armature support; a pair of connected pinions rotatably mounted upon the said spindle; a gear positioned within the hollow portion of the armature support engaging with one of the pinions and rigidly secured to the shaft; a second gear rotatably carried by the shaft and engaging with the other pinion, means for holding the second gear stationary, and a clutch within the hollow armature support for connecting the same directly to the said shaft.

6. The combination with a dynamo electric machine, of a shaft to be rotated; a member, independently rotatable by the armature of said machine; means for automatically clutching said member and said shaft, directly together; speed changing gearing located entirely within the axial confines of the dynamo, rotatable with said member, adapted for interposition between said member and shaft when part of said gearing is stopped, and means for stopping and holding part of said gearing to cause interposition of said gearing between said member and shaft and cause relative reduction of speed of said shaft.

7. The combination with a dynamo electric machine, of a shaft adapted to be driven by another source of power, and by said machine; a member, independently rotatable by the armature of said machine; means positioned within the axial confines of the dynamo for automatically clutching said member and said shaft directly together; speed changing gearing, rotatable with said member, adapted for interposition between said member and said shaft, when part of said gearing is stopped; and means for stopping and holding part of said gearing to cause interposition of said gearing and to release said direct connecting part when said member is rotating at a higher speed than said shaft.

8. The combination with a dynamo electric machine, of a shaft, an armature support rotatable about the said shaft, speed reducing gearing interposed between the armature support and the shaft, means for controlling said speed reducing gearing to prevent transmission of power therethrough and a clutch for positively connecting said armature support with the said shaft when the latter becomes the driver.

9. The combination with a dynamo electric machine, of a shaft, a hollow armature support rotatably mounted upon the said shaft, speed reducing gearing interposed between the armature support and the shaft, means for controlling said speed reducing gearing to prevent transmission of power therethrough and a clutch for positively connecting said armature support with the said shaft, when the latter becomes the driver, said speed reducing gearing being positioned within the confines of the hollow armature support.

10. The combination with a dynamo electric machine, of a shaft, a hollow armature support, rotatably mounted upon the said shaft, speed reducing gearing interposed between the armature support and the shaft, means for controlling said speed reducing gearing to prevent transmission of power therethrough, and a clutch for positively connecting said armature support with the said shaft when the latter becomes the driver, said clutch being positioned within the confines of the said hollow armature support.

11. The combination with a dynamo electric machine, of a shaft, a planetary gear carrier, planetary gears rotatably mounted thereon, means connected with the dynamo for rotating said gear carrier, a gear connecting the said shaft with the planetary gears, a second gear engaging with the planetary gear, a relatively stationary element, clutch means between the last mentioned gear and the relatively stationary element, and clutch means between the shaft and the gear carrier.

12. The combination with a dynamo electric machine, of a shaft, a planetary gear carrier, planetary gears rotatably mounted thereon, means connected with the dynamo for rotating said gear carrier, a gear connecting the said shaft with the planetary gears, a second gear engaging with the planetary gear, a relatively stationary element, clutch means between the last mentioned gear and the relatively stationary element, and a one way operating clutch for connecting the said gear carrier with the shaft when the latter acts as the driver.

13. The combination with a dynamo electric machine, of a shaft, a planetary gear carrier, planetary gears rotatably mounted thereon, means connected with the dynamo for rotating said gear carrier, a gear connecting the said shaft with the planetary gears, a second gear engaging with the planetary gears, a relatively stationary element, clutch means between the last mentioned gear and the relatively stationary element, and clutch means between the shaft and the gear carrier, and positioned entirely within the confines of the said carrier.

14. The combination of a dynamo electric machine comprising a primary rotatable member, a secondary rotatable member, speed responsive clutch means between said members and speed reducing gearing between the members including planetary gears.

15. The combination with a dynamo electric machine, of a shaft to be rotated; a cup shaped member of two diameters surrounding the shaft and carrying at its larger

periphery the armature windings and on the smaller periphery the commutator, a bearing between the shaft and cup shaped member at its smaller end, a disk rotatable about the shaft and secured over the open end of the said member forming a closure therefor, and speed reducing gearing connecting the armature with the shaft and positioned within the cup shaped member.

16. The combination with a dynamo electric machine, of a shaft to be rotated, a cup shaped member rotatably mounted upon the said shaft, a flange on the periphery of said member and adapted to retain the armature windings, a disk rotatable about the said shaft and secured to the open end of the cup shaped member to form a closure therefor, and speed reducing gearing connecting the armature with the shaft and positioned within the cup shaped member.

17. The combination with a dynamo electric machine, of a shaft therefor; a gas engine shaft adapted to be initially rotated by said dynamo electric machine; an armature support, rotatably mounted upon the first mentioned shaft, said support being provided with an opening; speed reducing gearing positioned within the said opening and connecting the armature support with the first mentioned shaft; and connecting means between the two shafts.

In testimony whereof I hereunto set my hand in the presence of two witnesses.

VINCENT G. APPLE.

In the presence of—

W. LINN ALLEN,
MARY F. ALLEN.
